CLAIM

The ornamental design for a hose reel as shown and described.

DESCRIPTION

FIG. 1 is a front elevational view of the hose reel;
 FIG. 2 is a rear elevational view thereof;
 FIG. 3 is a left-side elevational view thereof;
 FIG. 4 is a right-side elevational view thereof;
 FIG. 5 is a top plan view thereof;
 FIG. 6 is a bottom plan view thereof; and,
 FIG. 7 is a perspective view thereof.

The dash-dash broken lines shown in FIGS. 1-7 illustrate portions of the hose reel that form no part of the claimed design. The dot-dash broken lines shown in FIGS. 3, 4 and 7 define the bounds of the claimed design and form no part thereof.

1 Claim, 7 Drawing Sheets
